C. P. KUHL,

SNAP HOOK OR SHACKLE.

APPLICATION FILED JAN. 28, 1920.

1,363,516.

Patented Dec. 28, 1920.

UNITED STATES PATENT OFFICE.

CHARLES P. KUHL, OF GRINNELL, KANSAS.

SNAP-HOOK OR SHACKLE.

1,363,516.

Specification of Letters Patent. Patented Dec. 28, 1920.

Application filed January 28, 1920. Serial No. 354,728.

To all whom it may concern:

Be it known that I, CHARLES P. KUHL, a citizen of the United States, residing at Grinnell, in the county of Gove and State 5 of Kansas, have invented certain new and useful Improvements in Snap-Hooks or Shackles, of which the following is a specification, reference being had to the accompanying drawings.

10 This invention relates to snap hooks and particularly to snap hooks of relatively large size to be used for chains or cables, though I do not wish to be limited to this as smaller size hooks might be used for harness and for other purposes.

15 The general object of the invention is the provision of a snap hook of a particularly strong construction and in which the spring is fairly concealed and protected so that the 20 interior face of the hook or shackle is smooth and unobstructed, there being no projecting parts which might become engaged and injured by contact with a chain or cable.

25 A further object is to provide a shackle on the order of a snap hook in which the pivoted tang has such engagement with the hook portion proper that the tang has practically as much pulling strength as the body of the hook.

30 Other objects will appear in the course of the following description.

My invention is illustrated in the accompanying drawings, in which:

Figure 1 is a side elevation of a snap hook 35 or shackle constructed in accordance with my invention;

Fig. 2 is a fragmentary elevation of the tang, the adjacent portion of the shank being shown in section;

40 Fig. 3 is a face view of the tang;

Fig. 4 is a longitudinal elevation, partly in section, showing the pivotal connection between the tang and the body of the shackle or snap hook;

45 Fig. 5 is a section on the line 5-5 of Fig. 1;

Fig. 6 is a section on the line 6-6 of Fig. 1;

Fig. 7 is a side elevation of a slightly 50 modified form of the device.

Referring to the drawings, and particularly to Figs. 1 to 6, it will be seen that my shackle comprises a body portion 10 which at one end is bent in a relatively large circle 55 to form the hook portion 11, and at the

other end is bent to form a relatively small loop 12. The extremity of this loop 12 is reduced in thickness to form an ear 13 which is perforated. The walls 14 at the inner end of said earlike portion are concavely curved as illustrated in Fig. 4.

Mounted upon this ear 13 is a tang 15, one end of which is bifurcated or slotted to embrace the ear 13, this end being perforated for the passage of a transverse pivot pin or screw 16. The extremity of the loop portion 12 of the body 10 is bored longitudinally and the tang 15 is also bored longitudinally, and inserted in these bores is a spring 17 which is angular in form so as to urge the free end of the tang 15 out against and into alinement with the free end of the hook portion 11 of the body.

The free end of the hook portion 11 is longitudinally grooved as at 18, this groove 75 extending inward for a certain distance. The inner face of the hook portion 11 is notched as at 19 the groove 18 intersecting this notch. The outer wall of the notch 19 is approximately perpendicular to the outer 80 and inner faces of the hook portion 11. The tang 15 at its free extremity is reduced in width as at 20 and the end of this reduced portion is enlarged to provide a head 21, the outer face of which is transversely 85 rounded to suit the cross section of the material from which the shackle is made, the inner face of this head being beveled as at 22 so as to fit within the notch 19. The rear face 23 of the head is flat so as to engage 90 against the outer wall of the notch 19 and so that these two faces will be in contact and parallel to each other when the tang 15 is outwardly swung.

Of course, I do not wish to be limited to 95 the particular form of hook shown in Fig. 1, and in Fig. 7 I illustrate another form of hook, particularly adapted to be used in connection with ropes and harness, in which the shackle body 10^a is provided with the tang 100 15^a as previously described, there being however a ring or eye 24 swiveled to the shackle in an obvious manner.

Shackles or snap hooks of the character described may be made in different styles 105 for chains and cables, for harness and strap work and for ropes and lines. In case the spring 17 should break, the spring may be replaced by removing the screw 16, then separating the tang from the body. The old 110

spring may then be withdrawn and a new spring inserted and the parts again connected to each other.

I have provided a snap hook or shackle which is adapted for all purposes, yet is very simple in its construction and is extremely durable. When the tang is closed one side of the shackle or link has practically the same strength as the other side.

10 What I claim is:

1. A snap hook or shackle of the character described comprising a body, a tang, one extremity of the body and the adjacent extremity of the tang having pivotal engagement with each other, the pivoted end of the tang and the adjacent end of the body being formed with longitudinally extending, registering bores, and a spring inserted in said bores and yieldingly resisting oscillation of 20 the tang relative to the body.

2. A snap hook or shackle of the character

described comprising a loop shaped body, one extremity of which is reduced in thickness and transversely pierced, the opposite extremity having a notch on its inside face 25 and being formed with a groove extending from the end face into said notch, a tang provided at one end to fit said reduced portion and transversely pierced, the opposite end of the tang having a head adapted to 30 fit said notch and connected to the tang by a reduced portion fitting said groove, a screw connecting the tang to said reduced portion of the body, the pivoted end of the tang and the adjacent end of the body being formed 35 with longitudinally extending registering bores and a normally angular spring disposed in said bores and urging the tang to its outwardly projected position.

In testimony whereof I hereunto affix my 40 signature.

CHARLES P. KUHL.
